[57] **CLAIM**

The ornamental design for a service station island, as shown and described.

DESCRIPTION

FIG. 1 is a top plan view of a service station island showing our new design;

FIG. 2 is a side elevational view thereof, the opposite side view being a mirror image thereof;

FIG. 3 is a front perspective view thereof;

FIG. 4 is a front perspective view thereof, showing two service station islands; and

FIG. 5 is a front elevational view of that shown in FIG. 1, the rear elevational view being substantially a mirror image thereof.

FIG. 1

FIG. 2

FIG. 5

FIG. 3

FIG. 4
